No 825.

Wade & Wright's
Design for Coat-Stamp. Patent
to Richardson & Boynton.

Patented Aug. 19. 1850.

Res. 825

N. S. Bedder and Ezra. Ripley of Troy, N. Y.

Assignors to

Troy, Richardson & Boynton of the same place.

Letters Patent No. 825, Dated August 19th 1836.

The schedule referred to in these Letters Patent and making part of the same.

To all whom it may concern:

Be it known that we, N. S. Bedder and Ezra Ripley of Troy in the County of Rensselaer, and State of New York, have invented or produced a new and original design for a Cook Stove, which we call the "Peyton Air Tight," and we do hereby declare that the following is a full, clear and exact description of the same, reference being had to the annexed perspective drawing, making part of this specification.

The design of our Cook Stove is as follows, viz: - - -

A. is the top plate with the ornamental moulding (a).

B. is the front plate with the dotted moulding (b), and having the five doors (c), decorated with the panel ornaments (c) diamonds (d) and diamond sunk surface (e).

D, D, are the draught and damper doors, with the panel ornaments (f, f). E. is the jamb plate with the dotted moulding (g) and diamonds (h, h).

F, F, are the oven doors, with the panel ornaments (i, i) diamonds (j, j).

G. is the bottom plate with the ornamental mouldings (k) and (l).

H. is the leg with the ornamental work (m) and (n) disposed upon its face.

Having fully described our design for a cook stove, what we claim as new and desire to secure by Letters Patent is, The ornamental design and configuration of Cook
